UNITED STATES PATENT OFFICE.

JOHN HAMDEN RICHARDSON, OF MELROSE, MASSACHUSETTS, ASSIGNOR TO UNITED SHOE MACHINERY COMPANY, OF PATERSON, NEW JERSEY, A CORPORATION OF NEW JERSEY.

RESURFACING-TOOL.

1,083,297.

Specification of Letters Patent.

Patented Jan. 6, 1914.

Application filed December 8, 1912. Serial No. 735,264.

To all whom it may concern:

Be it known that I, JOHN H. RICHARDSON, a citizen of the United States, residing at Melrose, in the county of Middlesex and State of Massachusetts, have invented certain Improvements in Resurfacing Tools, of which the following description, in connection with the accompanying drawings, is a specification, like reference characters on the drawings indicating like parts in the several figures.

The general object of the invention is to provide a tool to be used in forming a smooth and even surface upon wood or other material or in restoring such a surface when scarred and worn, and one which shall be more efficient in action than tools of similar character hitherto employed.

The tool that illustrates the preferred embodiment of the invention is in the form of a rasp, which is intended primarily for use in resurfacing cutting blocks such as are employed in die presses and the like, but is obviously of general utility as a finishing tool, especially for plane wood surfaces.

In the cutting blocks referred to, it is important that the working surface should be perfectly plane and free from depressions or unevenness of any character, in order that the die may effect always a clean cut through the stock. At every cutting operation, however, the blade of the die is forced an appreciable distance into the surface of the block with the result that the latter rapidly becomes worn so as to make resurfacing necessary. It has been customary to employ for this purpose a rasp having teeth distributed regularly in the usual manner over all portions of its working face, and with a working member, moreover, extended to considerable length, which is necessary to insure the formation of a perfectly plane surface on the working face of the block. It has been found in practice, however, that in view of the hardness of the material of the block, and the fact that its working surface is formed across the grain, it is extremely difficult to force into such material the relatively large number of teeth with which a rasp of the usual form is provided sufficiently to make the tool effective on its forward movement. The tendency is for the tool to slip over the surface with but little abrading effect.

The principal object of the present in-

vention is to avoid the difficulty referred to and with this in view I have provided a tool which in its broadest aspect comprises a member having a working face formed with groups of abrading elements thereon alternating with blank portions between the groups, preferably in the general direction of operative movement of the tool. This tool may present a working member sufficiently extended to assure the formation of an even and regular surface on the block without being unduly difficult to operate in an effective manner because of the great number of abrading elements in action. The number of teeth provided may be relatively small, and in the preferred construction is substantially that of a tool of the usual form having a working face with an area half as great. At the same time the result accomplished is one that could not be obtained by merely thinning out or setting at wider intervals the teeth of a rasp formed in the usual way, since it has been found that in a rasp so constructed, with the number of teeth sufficiently reduced for the purpose in view, it is impossible to stagger the teeth in such a manner as to avoid the liability of the formation of ridges on the material in the operation of the tool. In the rasp of my invention each group of teeth is a unit the elements of which may be as fine and closely arranged as desired. By this construction any desired degree of smoothness may be obtained, and since the blank portions alternate with the groups of teeth in the general direction of operative movement of the tool, there is no tendency to pass over portions of the surface of the material without abrading effect. Such effect on the contrary is perfectly uniform on all portions of the material in the path of operative movement of the tool.

Other objects and advantages of the invention will appear from the following detailed description.

In the accompanying drawings: Figure 1 is an elevation of a tool that illustrates the preferred embodiment of the invention; and Fig. 2 is a perspective view of a portion of the front of the tool, showing the character of the working face.

The tool shown embodies a working member 1 in the form of a plate having a materially greater length than width, and presenting a generally plane lower or working

100

110

face 2 upon which are arranged groups of abrading elements 3 that alternate with blank portions 4 of the working face in the direction of the length of the working member. The abrading elements illustrated are in the form of teeth, which are arranged in staggered relation and may be as fine and closely set as desired, according to the character of the material to be worked upon 10 and the purpose in view.

The groups of teeth on the tool shown are in alinement in the direction of the length of the working member, but this is not essential, provided the groups are so arranged 15 that in the operative movement of the tool the surface of the material shall be abraded evenly without the formation of ridges. Nor is it necessary to employ abrading elements of the particular character 20 illustrated, since the invention may be given effect by the use of such elements in other forms.

The tool is provided with handles 5 and 6 secured to the plate 1 by screws, the heads 25 of which lie in the blank portions of the working face.

In operation the workman grasps the handles and moves the tool forward in the customary manner in the general direction 30 of the length of the working member with the working face adjacent to the surface of a cutting block or other object to be finished. The extension of the working member assures the formation of an even and regular 35 surface while at the same time, as previously pointed out, the smaller relative number of teeth in action permits the tool to be used efficiently for the purpose in view. The blank portions between the groups of teeth 40 serve also as clearance spaces for the chips and dust, by which the latter find a ready exit, and this is a further important element in the increased efficiency over prior constructions.

45 It will be understood that the invention is not limited to a tool having a generally plane working face, since the face may have other regular forms in conformity to the regular contour of the particular surface to be finished. Nor is it essential that each 50 group of teeth present the general outline of a rectangle as shown, since variations of this preferred arrangement may be adopted with good effect; and the relative extent of the 55 groups of teeth with reference to the blank portions may be varied as desired.

Other modifications also within the spirit and scope of the claims will suggest themselves to those skilled in the art to which my 60 invention relates.

Having described my invention, what I claim and desire to secure by Letters Patent of the United States is the following:

1. A rasp having upon its working face 65 distinct groups of abrading elements, said

groups being separated by relatively large blank portions of the face, and each group comprising a plurality of abrading elements distributed over a substantial portion of the area of the face both longitudinally and transversely thereof. 70

2. A rasp having upon its working face distinct groups of abrading elements, said groups being arranged in succession in the direction of operative movement of the rasp 75 and separated by blank portions of the face, the abrading elements of each group being distributed over successive units of area in the direction of operative movement of the face.

3. A rasp comprising a member having a working face with groups of teeth on said face alternating with blank portions between the groups, the teeth of each group being closely arranged and in staggered relation. 80

4. A rasp comprising a member having a working face with groups of teeth on said face alternating with blank portions between the groups, said groups being alined substantially in the direction of operative movement 90 of the face and the teeth of each group arranged in staggered relation.

5. A finishing tool comprising a member having an extended working face of regular contour with distinct groups of abrading elements thereon, each of said groups constituting a rasp of the requisite degree of fineness and formed to act upon all portions of the surface of the work in the path thereof in the operative movement of the tool, successive groups in said direction of operative movement being separated by relatively large blank portions of the face of the tool. 100

6. A tool for finishing plane surfaces, comprising a member having a substantially plane working face with groups of abrading elements on said face, said groups being separated by relatively large blank portions of the face that alternate therewith substantially in the direction of operative movement 105 of the tool, and each group comprising a plurality of abrading elements projecting from the face and distributed over successive units of area thereof in said direction of operative movement.

7. A tool for finishing plane surfaces, comprising a member having a substantially plane working face of materially greater length than width and arranged for operative movement substantially in the direction 110 of its length, said working face having groups of abrading elements thereon, said groups being arranged in succession in the direction of the length of the face and separated by relatively large blank portions of the face, each group comprising a plurality 120 of abrading elements distributed over the working face both longitudinally and transversely thereof.

8. A tool for finishing plane surfaces, com- 130

prising a member having a substantially plane working face of materially greater length than width, and groups of teeth on said face alternating with blank portions in the direction of the length of the face and between the groups, said groups being alined the teeth of each group arranged in staggered relation.

In testimony whereof I have signed my name to this specification in the presence of 10 two subscribing witnesses.

Correction in Letters Patent No. 1,083,297.

It is hereby certified that in Letters Patent No. 1,083,297, granted January 6, 1914, upon the application of John Hamden Richardson, of Melrose, Massachusetts, for an improvement in "Resurfacing-Tools," an error appears in the printed specification requiring correction as follows: Page 3, transpose lines 5 and 6; and that the said Letters Patent should be read with this correction therein that the same may conform to the record of the case in the Patent Office.

Signed and sealed this 2nd day of June, A. D., 1914.
